METAL WORKING TOOL

Filed Oct. 8, 1928

INVENTOR
Herman W. Johnson.

By *Ralph Keish*
ATTORNEY

UNITED STATES PATENT OFFICE

HERMAN W. JOHNSON, OF ST. LOUIS, MISSOURI, ASSIGNOR TO STILES-HERMAN MANUFACTURING COMPANY, OF ST. LOUIS, MISSOURI, A CORPORATION OF MISSOURI

METAL-WORKING TOOL

Application filed October 8, 1928. Serial No. 311,069.

This invention relates generally to metal-working tools and, more particularly, to a certain new and useful improvement in tools especially adapted for removing dents and the like from automobile fenders, my invention having for its chief object the provision of a tool of the type and for the purpose stated which is simple and inexpensive in construction, compact and durable, readily engageable with the fender, conveniently and easily operatively manipulated, and efficient in the performance of its intended functions.

And with the above and other objects in view, my invention resides in the novel features of form, construction, arrangement, and combination of parts hereinafter described and pointed out in the claims.

In the accompanying drawing,—

Figure 1 is a perspective view of a metal-working tool of my invention, illustrated as in working operation upon a fender;

Figure 2 is a plan or edge view of the tool;

Figure 3 is a side elevational view of the tool, showing the tool in operative working engagement with a fender;

Figure 4 is a detail section of the tool, taken approximately on the line 4—4, Figure 2; and

Figures 5 and 6 illustrate in elevation interchangeable hammer-heads of the tool.

Referring now more in detail and by reference characters to the drawing, which illustrates a preferred embodiment of my invention, the tool includes a pair of tongs A, which comprises a suitably elongated leg or blade 1 formed or provided at an end with an angular enlargement or head 2, which latter, in turn, is formed or provided with a jaw 3 preferably, for purposes presently appearing, flat on its inner face, as at 4, all as best seen in Figures 2 and 3. Disposed flatwise in relation to the leg 1 and pivotally secured thereto, as at 5, for hinge-movement, is the other leg 6 of the tongs A, which leg 6 is likewise provided at an end with a head 7 having a jaw 8 opposed to and for co-operation with the jaw 3 and similarly preferably flat on its inner face, as at 9, also all as best seen in Figures 2 and 3. The tongs A, in the manipulation of the tool, are adapted for de-

tachable clamping engagement at its co-operating jaws 3, 8, with the fender B or other work to be repaired, and to obviate marring of the fender one or both of the jaws 3, 8, is preferably provided with a suitable cushioning member 10, such, for instance, as a layer of felt or other analogous material.

Pivots secured, as by means of a stud-bolt 11 and wing-nut 12, or the like, to the tong-leg 1 at its head 2, is a slotted guide and lever-fulcrum member C, and disposed for lengthwise shiftable movement or adjustment through the member C, is a suitably elongated lever or hammer-handle D, the member C being provided with a set-screw or the like 13 for impinging engagement with lever D for releasably retaining the lever D in adjusted or shifted position relatively to the member C.

Slotted, as at 14, to adjustably fit upon the lever D, is a hammer-head E of suitable contour and configuration for the work to be accomplished, the head E being provided with a set-screw 15 or the like for impinging engagement with the lever D for detachably retaining the head E in adjusted or shifted position on the lever D.

In use and operation, the tongs A are detachably clampwise or grippingly engaged at its cooperating jaws 3, 8, with the fender B from which the dent is to be removed. The lever D equipped with a head E is then adjusted relatively to the guide C and the work to be performed, whereupon, with the member C as its fulcrum, the lever D is manually manipulated swingably as a hammer in effecting, through impacting engagement as its head E with the fender B or other work, removal of the fender-dent.

For dents or the like variously located in the fender B, it may be desirable to effectively employ differently shaped hammer-heads, and to that end a head, as, for instance, the head E', illustrated in Figure 6, may be readily interchanged upon the lever D for the head E.

The tool may be easily engaged with the fender or other work and conveniently operatively manipulated without removal of the usual wheel. I may add that from actual

use the tool has been found exceedingly efficient in the performance of its intended functions.

It is to be understood that changes in the form, construction, arrangement, and combination of the several parts of my new tool may be made and substituted for those herein shown and described without departing from the nature and principle of my invention.

Having thus described my invention, what I claim and desire to secure by Letters Patent is:

1. A manually operable metal-working tool including, in combination, tongs comprising a pair of pivotally-connected jaws adapted co-operably for detachable gripping engagement with the work, and a hammer fulcrumed upon the tongs for swingable impacting engagement with the gripped work.

2. A manually operable metal-working tool including, in combination, tongs comprising a pair of pivotally-connected jaws adapted co-operably for detachable gripping engagement with the work, and a hammer adjustably fulcrumed upon the tongs for swingable impacting engagement with the gripped work.

3. A manually operable metal-working tool including, in combination, tongs comprising a pair of pivotally-connected jaws adapted co-operably for detachable gripping engagement with the work, a slotted guide pivotally mounted on one of the jaws, and a hammer having its handle projecting through the guide and fulcrumed by the guide upon the tongs for swingable impacting engagement with the gripped work.

4. A manually operable metal-working tool including, in combination, tongs comprising a pair of pivotally-connected jaws adapted co-operably for detachable gripping engagement with the work, a slotted guide pivotally mounted upon one of the jaws, a hammer having its handle slidably projecting for adjustment through the guide and fulcrumed by the guide upon the tongs for swingable impacting engagement at its head with the gripped work, and means for adjustably securing the handle in adjusted position to the guide.

5. A manually operable metal-working tool including, in combination, tongs comprising a pair of pivotally-connected jaws adapted co-operably for detachable gripping engagement with the work, in combination with a hammer fulcrumed upon one of the jaws for swingable movement, and a head mounted for adjustment on the lever for delivering, on swingable movement of the lever, an impacting blow on the gripped work.

6. A manually operable metal-working tool including, in combination, tongs comprising a pair of pivotally connected jaws

adapted co-operably for detachable engagement with the work, in combination with a lever fulcrumed upon one of the jaws for swingable movement, a slotted head mounted for adjustment upon the lever, and means engageable with the head and lever for securing the head in adjusted position upon the lever, the head being adapted, on swingable movement of the lever, for imparting an impacting blow upon the gripped work.

7. A manually operable metal-working tool including tongs comprising a pair of pivotally-connected jaws adapted co-operably for detachable engagement with the work, in combination with a lever fulcrumed upon one of the jaws for relative swingable movement, and hammer-heads adapted interchangeably for support on the lever for impacting engagement with the gripped work on swingable movement of the lever.

In testimony whereof, I have signed my name to this specification.

HERMAN W. JOHNSON.
